UNITED STATES PATENT OFFICE.

LOUIS JACOBS, OF CHICAGO, ILLINOIS.

SLEEPING-BAG.

1,267,551.

Specification of Letters Patent. Patented May 28, 1918.

Application filed September 10, 1917. Serial No. 190,465.

To all whom it may concern:

Be it known that I, LOUIS JACOBS, a citizen of the United States, residing at Chicago, in the county of Cook and State 5 of Illinois, have invented certain new and useful Improvements in Sleeping-Bags, of which the following is a specification.

This invention relates to improvements in sleeping bags and more particularly to a 10 bag intended for outdoor use and arranged to provide ample protection to the user from the elements.

One of the objects of my invention is to provide a sleeping bag in which the head 15 portion is held in erected position by a collapsible frame forming a sort of tent structure for the protection of the user's head.

Another object of the invention is to provide such a device in which the head structure is provided with a canopy held in position by a collapsible frame permitting, when so desired, the complete inclosure of 20 the head structure as a protection from storm.

Still another object of the invention is to provide such a sleeping bag which may be readily used either as a stretcher or as 25 a hammock.

30 A still further object is to provide such a sleeping bag of sturdy, rugged construction providing complete protection to user and at the same time of such a character to permit its being readily folded into 35 small space for transportation.

Still other and further objects will become readily apparent to those skilled in the art from a consideration of the following description and drawings wherein:

40 Figure 1 is a perspective view of my improved sleeping-bag with the cover thrown back and the canopy erected.

Fig. 2 is a perspective view of the head 45 portion of the bag with the canopy thrown back.

Fig. 3 is a perspective view of the head portion of the bag with the canopy erected and connected to the cover for complete protection against storm;

50 Fig. 4 is a perspective view of the head structure supporting frame.

Referring now to the drawings where I have illustrated the preferred embodiment of the invention, the numeral 10 indicates 55 the bottom of a sleeping bag of generally rectangular outline and of dimensions such

as to provide ample room for the user with a number of blankets such as may be necessary in severe weather. Side-walls 11 and 12 and end walls 13 and 14 extend upwardly 60 from the bottom to provide with the cover 15 an envelop forming the body part of the bag. A marginal strip 16 extends around the envelop from the bottom portion providing a reinforcement as well as material 65 in which to insert gromets 17 by means of which the bag may be staked out on the ground or suspended on poles to form a stretcher. The gromets in the end of the marginal strip 16 may be utilized for connection with a spreader should the user desire to suspend the bag in the manner of a hammock.

The cover 15 is seamed to the side-walls and bottom end wall for a short distance 75 from the foot to form a permanent inclosure for the lower end of the envelop and its remaining portion is detachably secured to outer, upper edge portions of the side-walls 11 and 12 by means of the glove- 80 fasteners 19-19'. The connections between the sides and bottom are suitably seamed and to further strengthen the structure, I have extended reinforcing strips 20 across the bottom of the bag between opposite 85 pairs of gromets 17.

At the head portion of the bag I have increased the height of the side walls 11 and 12 as at 21 and 22 and similarly increased the height of the end wall 13 so 90 as to provide a deeper envelop at this portion than throughout the body portion of the bag. The head structure is held in erected position by means of a collapsible wire frame illustrated in Fig. 4 comprising 95 a rectangular end section 23 corresponding in width and height to the end member 13 of the bag and side-members 24 and 25 pivoted at 26 upon the vertical bars of the end frame 23. This frame is indicated in 100 Fig. 2 and the upper edges of the sides 21 and 22 are folded over as at 28 to engage the upper horizontal bars of the side frames 24 and 25 being secured in this position by means of the glove-fasteners 29.

105 A canopy or head cover 30 extends from the upper edge of the head end 13 to form a roof or shelter for the head portion of the bag, it being seamed to the upper edges of the sides for a short distance to a point indicated at 31 and from there on is separable 110 from the side walls so that it may be thrown

back into the position indicated in Fig. 2 as when shelter for the user's head is not desired. A transverse rod 32 is secured across the canopy on the line indicated at 33 and 5 at its ends is provided with loops 34 into each of which is linked the looped ends of a pair of rods 35 which may be stuck into the ground as indicated in Figs. 1 and 3 to support the canopy in erected position. The 10 forwardly extending rods 35 engage loops formed by bending inwardly the ends of the side-frames 24 and 25 of the head frame as at 36 so as to hold the sides of the head frame in spaced-apart or opened out position. A pair of rings 37 are secured to the 15 outer end portion of the canopy for co-operation with snap-fasteners 38 secured to the end portion of the cover 15 so that they may be fastened together as indicated in Fig. 3 20 to completely inclose the head structure and protect the user from the elements. Ventilators 39 are inserted in the side-walls of the head structure to provide a supply of fresh air when the hood is completely 25 closed.

In use the bag may be placed upon the ground with the cover thrown back as indicated in Fig. 1. The user may then erect the head canopy in which ever position he 30 may desire depending upon the weather and can then place his blankets within the envelop and after lying down, draw up the cover and snap it in position in engagement with the side walls. The head canopy may 35 then be altered to suit his convenience, being either thrown back as indicated in Fig. 2 affording no protection, elevated to the position shown in Fig. 1, or drawn into the position shown in Fig. 3 completely protecting 40 him from storm.

To collapse the structure the snap-fasteners 29 are disengaged freeing the sides of the head frame and permitting their being folded inwardly against the back frame 23. 45 The entire bag can then be rolled up about this frame forming a rectangular pack easily carried and occupying but little space.

Whereas I have illustrated and described 50 but a single embodiment of my invention, it will be evident to those skilled in the art that many modifications or changes may be made therein, without departing from the spirit of the invention or the scope of the 55 appended claims.

Having described my invention, what I claim is:

1. A sleeping bag comprising a fabric en-

velop with bottom, side and end walls, and a cover; the end and side walls adjacent the 60 head end of the bag having a vertical height greater than that of the sides of the body portion, and a collapsible frame positioned entirely within the head end of the bag for holding the end and side walls 65 throughout their greatest height in erect position.

2. A sleeping bag comprising a fabric envelop, a head protecting structure having side and end walls; a rectangular wire frame 70 positioned within the bag for holding the end wall in erect position, and rectangular side frames positioned within the bag pivoted on the ends of the aforesaid frame for holding the side walls in erect position.

3. A sleeping bag comprising a fabric envelop, a head protecting structure having side and end walls; a rectangular wire end frame for holding the end wall in erect position, rectangular side frames pivoted on the 80 ends of the end frame for holding the side walls in erect position, and separable fasteners carried by the upper edge portions of the side walls for engagement with the side frame.

4. A sleeping bag comprising a fabric envelop having a bottom and side walls, a head protecting structure having side and end walls formed as a continuation of the side walls of the bag but of a greater height, 90 means inside the head structure for holding the side and end walls of the head structure in erect position, a canopy extending from the upper edge of the end wall over the head structure, a transverse rod secured to the canopy near its end, and ground engaging rods secured to the ends of the transverse rod to hold the canopy in erect position.

5. A sleeping bag comprising a fabric envelop, a head protecting structure having 100 side and end walls, a frame comprising end and side members foldable upon each other for holding the end and side walls in erect position; a canopy extending from the upper edge of the end wall over the head structure, a transverse rod secured to the canopy near its end, ground engaging rods secured to the ends of the transverse rod to hold the canopy in erected position; and loops formed 105 in the side members for engagement by the ground engaging rods to hold the frame in open position.

In testimony whereof I hereunto set my hand.

LOUIS JACOBS.
